REEL

Anthony Foukal, Cleveland, Ohio, assignor to
Truscon Steel Company, Youngstown, Ohio, a
corporation of Michigan

Application February 26, 1936, Serial No. 65,879

5 Claims. (Cl. 242—77)

The present invention relates to metal reels and more particularly to reels of the type that are used for lead covered or other cables, or other windable materials. There has been much activity recently in the development of such structures to replace the commonly used wooden reels.

An object of the invention is to provide a novel metal reel structure that has ample strength and rigidity to resist the rough usage to which it is subjected and which will be sufficiently light in weight, to be capable of being shipped without unreasonable expense.

Another object of the invention is to provide a reel which may be assembled from elements without the necessity of careful fabrication of such elements to accurate dimensions.

Still another object is to provide a reel which may be assembled easily and quickly, and in which all joints are readily available for assembly welding, examination, or repairs.

Another object is to provide means for securing the end of a cable after it has been wound upon the reel.

In the accompanying drawings:

Figure 1 is an elevation of one end of a preferred embodiment.

Figure 2 is an elevation partly broken away on the line 2—2 of Figure 1.

Figure 3 is a sectional view on the line 3—3 of Figure 2.

Figure 4 is a perspective view of a section of the reel showing the method of supporting the drum.

Figure 5 is a sectional view showing the method of joining the ends of the cable drum, on the line 5—5 of Figure 2.

Figure 6 is a sectional view taken on the line 6—6 of Figure 1.

Figure 7 is a sectional view taken on the line 7—7 of Figure 1, the structure being shown with the drum removed in order to clearly disclose the structure underlying it.

Figure 8 is an elevation showing the end of a modified structure.

Figure 9 is a view in elevation partly in section, the section being taken on the line 9—9 of Figure 8.

Figure 10 is a perspective view of a portion of the end structure showing the method of supporting the drum.

Figure 11 is a sectional view taken longitudinally through one end of one of the spokes.

Figure 12 is a sectional view taken on the line 12—12 of Figure 11.

Figure 13 is a sectional view taken on the line

13—13 of Figure 8, with the drum being omitted to show the underlying structure.

Describing the drawings more particularly the reel consists generally of an axle and a head mounted at each end. In the preferred embodiment, the heads are mounted upon an axle 14 which is preferably tubular. The axle performs two functions. It strengthens the structure and acts as a guide for a bar inserted through its hollow center for supporting the reel, for hoisting it, or for reeling the contents. In each end of the axle 14 may be mounted a smaller hub portion 15 which may be tubular, and which advantageously may be of a size to afford a sleeve fit with the interior of the axle 14, and which extends beyond the ends of the axle 14, the ends of which form shoulders 16. Mounted upon the hub portion 15 at each end of the axle is a plate 17, shown here as being circular, but which may be of any suitable shape, and having a flat outer surface 18. The plates 17 are butted against the shoulders 16 and secured both to the axle 14 and to the hub 15, as by welds 19.

A plurality of spokes 20 have their end portions secured to the outer surface 18 of each plate 17 and extend radially beyond the margins of the plates 17 to points adjacent the outside periphery of the reel. These spokes 20 are preferably secured to the plates by means of welding 21. The spokes are here shown of channel material, with the webs turned inwardly and the legs extending outwardly, but they may be formed of any suitable metal structural shapes, including, by way of example besides channels, any form of tubing, angle bars, or shaped bars, such as I and T-bars.

At the outer ends of the spokes, they are engaged by and secured to, as by welding at 22, reinforcing and rolling rims 23. These rims which are circular may advantageously be made of angle bars, which as shown in cross section in Figure 2, have flat outer surfaces and flanges extending inwardly along the inner sides of the spokes 20. The outermost portions of the spokes are inset as shown at 24 in order to provide flush joints with the inwardly extending flanges of the rims. The rolling rims 23 besides being formed of angle bars may be made of channels, or any other form of angle having perpendicular members, such as T-bars or I-beams.

At a point between the margins of the plates 17 and the reinforcing and rolling rim 23, members for spacing the heads on the reel and for supporting a drum structure, are provided. These members are shown as being flat-sided rectangu-

lar bars 25, although they may be of suitable structural shapes, such as channels or round rods or tubing. The bars are secured, as by welding, at 26 to the opposite sides of each spoke, and 5 they extend between the respective spokes of the two heads, thus acting to space the heads.

Upon the spokes which form each head of the drum, respectively, are mounted side shields 27. These side shields are in the form of flat annular rings and may be formed of two or more segmental sections 28 having their meeting ends 29 welded together. The shields 27 are mounted 10 on the inner faces of the spokes 20 preferably by welding as at 30, and their outer margins extend substantially to the outer surfaces of the 15 rims 23. From Figure 2 it will be seen that the shields 27 are flat between their margins, this being permitted by the flush joint between the spokes and the rims 23.

20 In order to mount a drum upon the members 25 between the heads, a plurality of rings 31 are mounted upon the outer surfaces of and surrounding the bars 25, these rings being shown here as round, but which may be of any other 25 suitable structural shape capable of being formed into a circle. One of the rings 31 is positioned adjacent the side shield 27 on each of the heads of the reel and the inner margin of each side shield may be bent inward and along the adjacent ring in the form of a flange 32 which may be tightly rolled around a portion of the surface of the ring. The purpose of these flanges is to afford tight joints between the side shields and the drum structure in order to isolate the cable 35 receiving portion of the reel from the hollow center and prevent the entrance of dirt, grit and other abrasive elements which may otherwise sift through and abrade the lead or other protective covering of the cable while the reel is in transit 40 or storage.

A substantially cylindrical drum 33 is secured about the rings 31, the outer surfaces of which it engages and to which it may be secured as by suitable welds 33b. The drum may be formed of 45 a single metal plate formed into a cylinder. One end 33a may be inset in order to provide a lapped joint with a flush outer surface and to allow for irregularities as will be more fully described later.

50 In the modification shown in Figures 8-13 inclusive, the structure is substantially the same, with the exception that the spokes 34 are formed of channels with their webs 35 turned outwardly and their leg portions 36 engaging the plate 17 and the side shields 27.

Referring to Figure 9 it will be seen that the leg portions 36 of these channels may be cut away or deformed in any suitable manner at 37 to afford a seat for the inwardly extending flanges of the 60 rolling rims 38, and providing a continuous flat surface for the side shields 27.

In both modifications means are provided for withdrawing the cable from the reel. These means take the form of a slot 40 which is formed 65 by a cut out portion of one of the side shields 27 and which extends outwardly from the inner margin thereof. The slot 40 lies preferably equally spaced from and between two of the spokes. In order to guide the cable smoothly from the reel, 70 and to prevent the lead or other sheathing from being damaged, an outwardly bent tongue 41 is provided at each end of the slot. This tongue is formed from the material of the head 27, the latter being slotted at 42 in order to permit the 75 tongue to be outwardly curved to form a guide.

as shown in Figures 7 and 13. A shield member 43 may be attached to the adjacent spokes in order to protect the end of the cable while a reel is in transit, and while it is not in actual use.

Means are provided for fastening the end of a cable, which has been wound on the reel. To this end in the reenforcing and rolling rims 23 there are punched holes 44, the edges of which are rounded off to prevent cutting. In certain of the spokes, as for example, every other one, are holes 45 for the reception of eye bolts 46. A rope or cord may be attached to the end of a cable wound upon the reel and led out through one of the holes 44 and thereafter be led to and tied to the closest of the eye-bolts. The combination of 15 the holes 44 and the eye-bolts 46 permits the end of a cable to be fastened at any point, and permits adjustment of the tension thereon, the eye-bolts 46 being provided with nuts 47, by means of 20 which the position of the eyes may be adjusted. Loops 48 are also provided on certain of the spokes and a rope may be tied to one of these when it is not necessary to make an adjustment. The spokes at each side of the slot 40 are both 25 provided with a loop 48 to which the end of a cable near or passing through the slot may be fastened.

The chief advantage of the reel is its ease of construction which may be in the following manner. A plate 17 is laid on a flat surface and surrounded by a rim such as 23 with an approximately even space between them. The spokes thereafter are positioned with their outer ends butting against the flange of the rim and it will be seen that their length may vary inasmuch as 35 there is ample space on the plate for welding them, and it is immaterial how close their ends extend to the hub as long as the space between the plate and rim is even and the spokes are 40 sufficiently long to provide strong joints with the plate.

The drum section is preferably assembled separately from the heads in the following manner. The rings 31, may be placed on a suitable jig, and the sheet or plate which forms the drum 33 45 wrapped tightly around them. One end of the sheet is preferably inwardly displaced as shown in Figure 5 at 33a to allow a flush joint to be made between it and the other end. This gives a strong joint in spite of any irregularity on the part of 50 the drum due to variations in the rings. After wrapping the drum around the rings, its ends may be suitably welded together and the sheet welded to the rings thus forming a substantially cylindrical structure.

The drum assembly, having been completed, it may be assembled with the heads, which have been tightly clamped against its ends, by inserting the bars 25 and positioning them tightly against the inner surfaces of the rings 31, and 60 welding them to the sides of the radial spokes 20 as at 26. The axle 14 and hubs 15 may be inserted in the structure at the time of mounting the heads. The flanges 32 of the heads may be rolled around the end rings 31. The formation 65 of the tongues 41 from the material of the side shield obviates the necessity for forming a separate piece and securing it to the head.

By assembling this structure in this manner it will be readily seen that variations in the spacing 70 of the heads, in the shape and size of the rings 31, in the width of the drum proper, in the radial location of spokes, in the width of the spokes, in the central location of the drum assembly, and other similar irregularities, such as are common 75

to fabricated structures, will not be of great moment, since the bars 25 are so placed as to compensate and allow for the various assembly irregularities that may exist on any individual reel undergoing construction.

The reel is strong due to the fact that the individual and component parts are so tied together that any shock or blow to any part of the reel is distributed to all of the various other parts, each one of which lends its particular strength to the whole.

The ease with which the reels may be assembled, due both to the accessibility of the welded joints and to the fact that careful dimensioning and shaping of all of the elements is not necessary, materially reduces the cost of manufacturing a complete reel.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim is:

1. In a reel for cables, having a central drum, a ring for supporting the drum and located inside and closely adjacent the end of the drum, a head having means for supporting the said ring, a side shield mounted on the head and having a central aperture, and a flange on the inner margin of the side shield extending inwardly inside of the ring and closely engaging the surface of the ring.
2. In a reel for cables having spaced heads, spacing and supporting members extending between the heads, a ring closely adjacent each of the heads and mounted on the outer sides of the

spacing and supporting members, a drum mounted on the outer sides of the rings, and a side shield mounted on each of the heads and extending radially outward from the drum, an inwardly extending flange on each of the side shields engaged between the spacing and supporting members and the rings supported by them.

3. In a reel for cable having spaced heads comprising each a plurality of flat-sided radial metal spokes, a cylindrical drum mounted between the heads, and annular rings positioned within the drum for supporting it, means for supporting the rings and spacing the heads comprising metal bars having flat sides, the flat sides of the said bars being welded to the flat outer sides of the spokes, and the bars being wholly within the circumference described by the inner surfaces of the drum supporting rings, the rings spacing the bars from the drum throughout their entire lengths and supporting the drum upon the bars.

4. In a reel for cables comprising spaced heads including a plurality of radial, flat-sided metal spokes and a cylindrical drum extending between the heads, a plurality of bars extending respectively between spokes of the respective heads, the bars being welded to the outer flat sides of the spokes, between which they extend, and the drum being supported at spaced intervals upon the bars.

5. In a reel for cables comprising spaced heads including a plurality of radial flat-sided spokes, and a cylindrical drum extending between the heads, a plurality of flat-sided bars extending respectively between spokes of the respective heads, the flat sides of the bars being secured to the flat outer sides of the respective spokes between which they extend, and the flat surface of each bar extending in substantially the same plane throughout its length.

ANTHONY FOUKAL.
